UNITED STATES PATENT OFFICE.

HENRY TRUMBULL, OF PLAINVILLE, CONNECTICUT, ASSIGNOR TO THE TRUMBULL ELECTRIC COMPANY, OF PLAINVILLE, CONNECTICUT, A CORPORATION OF CONNECTICUT.

SWITCH.

SPECIFICATION forming part of Letters Patent No. 758,120, dated April 26, 1904.

Application filed July 18, 1903. Serial No. 166,206. (No model.)

To all whom it may concern:

Be it known that I, HENRY TRUMBULL, a citizen of the United States, and a resident of Plainville, in the county of Hartford and State 5 of Connecticut, have invented certain new and useful Improvements in Switches, of which the following is a specification.

The invention relates to the class of devices commonly used in the art for controlling electric circuits, and pertains more particularly to the special class of devices known as "knife-switches." In such devices it has been a common practice to provide a blade or knife, or a pair of blades, hinged at one end to a pair of terminals and adapted to be brought into contact with coöperating terminals at the opposite end, in such devices the terminals having been ordinarily made of metal and joined by screws or other means to a binding-post section to 20 receive the line-wire.

The object of the present invention is to provide a simple, inexpensive, and compact device pertaining more particularly to the stationary contacts which coöperate with the blade of the switch and at the same time to provide perfect carrying capacity for the connections between the binding-post and switch-terminals.

A further object is to produce a combined 30 terminal and switch-contact that is made from a single piece of metal, which may be readily secured in place and which will give a perfect contact with the blade of the switch.

A still further object is to produce a stop 35 device which may be used in conjunction with the stationary contacts and which will determine the depth to which the movable blade or contact may be inserted in the stationary contact.

Referring to the drawings, Figure 1 is a 40 perspective view of a switch embodying the improvements. Fig. 2 is a perspective view of one of the knife-switch contacts. Fig. 3 is a rear elevation of the contacts shown in Fig. 45 2, showing the stop. Fig. 4 is a modified form of contact with outwardly-turned ears in place of the inwardly-turned ears shown in Fig. 2. Fig. 5 is a view in elevation of the contact

shown in Fig. 4, illustrating the stop. Fig. 6 illustrates a vertical section of the knife-switch contact and terminal attached thereto, the parts being separated to better illustrate the construction. Fig. 7 is a plan view of the parts shown in Fig. 6.

In the accompanying drawings the numeral 55 1 denotes the base or support, of insulating material, which may be made from any suitable non-conducting material, and 2 3 designate clips or contacts in which the movable blades 4 5 are pivoted. These blades are joined together at one end by a cross member 6, to which is secured an ordinary handle for throwing the blades 4 5 into and out of contact with the contact members 7 8. It is to be noted that in each of the contact members 60 7 and 8 and 2 and 3 a single piece of metal forms both the contact and the binding-post by which the line-wires are attached.

The contacts 2 and 3, which form the pivotal supports for the blades 4 5, are substantially 70 alike, inasmuch as they are formed of a single piece of metal; but in the case of the contact 3 there is shown a support with upwardly-extending side members which are bent backward and downward upon themselves, forming 75 a very rigid and somewhat thickened support for the pivot 9. In the case of the contact 2, which is shown in slightly-modified form, the downward portion has been omitted; but in either case the binding-post sections 10 and 11 80 are formed integral with the supporting members 12 13. These combined binding-posts and hinged clips are secured to the base of insulating material in any desired manner, as by screws, and each of the members, adjacent to 85 the point where the line-wires are attached, are provided with upturned ears 14, which securely hold the end of the line-wire in position with relation to the binding-screws 15 16.

The clips or stationary contacts 7 and 8 are 90 of similar form to the hinge-clips. They have a binding-post section 17, with upturned ears 18 and contact-jaws 19, formed integral with the blade-embracing section 20. This section has upwardly-projecting side parts and down-turned ends adjacent to each other, which form 95

a spring gripping-jaw for the switch-blades. These clips are secured to the base through the medium of stops 21, which comprise a small block of metal arranged to fit between the side 5 walls of the clip and are provided with an upwardly-extending projection or stop 22, which is arranged transversely to the slot or opening 23, formed between the spring-jaws. This stop is provided with a screw-thread in the section 10 21, which co-operates with a screw 24 and by which the combined clip and binding-post is secured to the base 1.

The purpose of the stop 22 is to prevent the blades 4 5 passing into the openings 23 to too 15 great an extent, and serve as an indicator to show the operator by the "feel" of the switch when the blades have been properly inserted in the clips.

There are material advantages in forming 20 the clip and binding-post from a single piece of material, as sheet metal, which is bent to form. Absolute contact is insured between the line-wire and the switch-blades, and all of the parts of the clips may be readily formed 25 by dies with little or no waste of material.

In Figs. 4 and 5 of the drawings there is shown a slightly-modified form of clip in which the binding-post section 25 is provided with upturned ears 26 and an opening to receive 30 the binding-screw, as at 27. Integral with this binding-post section are upwardly-extending walls 28, which converge, as at 29, and being continued form parallel walls 30 with outwardly-projecting lips 31, the latter 35 arranged to insure proper engagement of the switch-blades. A stop 32 is adapted to be used with this clip, as in the case of the clips above described, and is of the same general formation. There is a special advantage in 40 providing an independent stop in the clips, inasmuch as the contact and binding-post members are usually formed of copper, and the stop may be formed of a harder material, in which a screw-thread may be cut, and which 45 will bear much greater strains than will the soft copper of the clip.

The same advantages above recited may of course be secured in practically the same manner by using the arrangement shown in 50 Figs. 6 and 7 of the drawings. In these figures the contact 7 has the side walls 20 and downturned end walls 19, together with the parts 17 and lugs 18, arranged identically as heretofore described; but in place of using a 55 stop having an upturned lug, as illustrated in Fig. 3 at 22, the screw 35 projects through the stop-plate 36, which is preferably of hexagonal form and of a harder material than the body portion of the contact. This screw extends upward adjacent to the opening between the jaws, and its end 37 forms the necessary stop for preventing too great depression of the blade. There is an advantage in using

this construction, inasmuch as the screw 35 serves a double purpose in that it holds the 65 contact to the base and also provides the necessary stop for the blade.

In Figs. 6 and 7 there is also illustrated the preferred form of terminal contact for use in connection with the contact-clips of the switch. 70 These terminal contacts 38 are preferably formed of seamless tubing crushed down at one end, as at 39, and punched, as at 40, to fit over the binding-screw 41. This screw is inserted from below through the base and operates with a nut 42 to hold the terminals 38 in place. Such a terminal may be made at the lowest possible cost and insures proper conductance of the current, inasmuch as it may be made of the finest copper. The line-wire 80 of course is inserted in the open end of the terminal 43 and may be secured therein by soldering or by a set-screw, if desired. It will of course be seen that the body of the contact is made from a single piece of metal 85 with the upturned ears 18 and all of the parts integral, and the crushed tubular terminal member may be easily inserted between the ears 18 and secured in place by the nut and screw. 90

What I claim as my invention, and desire to secure by Letters Patent, is—

1. A contact for switches comprising a binding-post section and a blade-engaging section formed from a single piece of material bent 95 to shape, an insulating-base and screw for securing said binding-post section to the base and a nut arranged within the side walls of the binding-post section and adapted to be engaged by the screw, said nut having an extended lug upturned to form a stop.

2. In a switch-contact comprising a binding-post section and a blade-engaging section formed of a single piece of material bent to shape, an insulating-base, a screw for securing 100 said binding-post section to the base and a nut co-operating with said screw and arranged between the side walls of the binding-post section and having an upturned lug forming a stop, said nut formed of a different material 110 from that of the binding-post.

3. The combination of an insulating-base, a switch-contact including a binding-post section and a switch-blade section adapted to be engaged by the switch-blade, the two sections formed of a single piece of material bent to shape, the switch-blade section including inwardly and downwardly turned portions, a screw for securing said contact to said base, a nut to co-operate with the screw and having an 115 upturned lug forming a step between the walls of the contact.

HENRY TRUMBULL.
